FIG. 4 is a front plan view thereof;

40/124.4; 229/102.5, 115, 116, 931; 248/459;

FIG. 5 is a back plan view thereof;

211/85

FIG. 6 is a top plan view thereof;

See application file for complete search history.

FIG. 7 is a bottom plan view thereof; and,

(56) **References Cited**

FIG. 8 is a perspective view as seen from the top and right side thereof in an unassembled state.

U.S. PATENT DOCUMENTS

The broken line showing in FIGS. 1, 2, 5, 6, and 8 is included for the purpose of illustrating an aperture and forms no part of the claimed design.

The broken lines in FIGS. 1, 2, 5, 6, and 8 represent an aperture through which items, such as ballot/sweepstake entries, may pass through and are used to illustrate that such aperture may take any shape or size.
